(57) **CLAIM**

The ornamental design for a thermostat, as shown and described.

DESCRIPTION

FIG. 1 is an upper perspective view of an embodiment of a thermostat;

FIG. 2 is a lower perspective view of the thermostat shown in FIG. 1;

FIG. 3 is a front view of the thermostat shown in FIG. 1; FIG. 4 is a rear view of the thermostat shown in FIG. 1; FIG. 5 is a left-side view of the thermostat shown in FIG. 1; FIG. 6 is a right-side view of the thermostat shown in FIG. 1;

FIG. 7 is a top view of the thermostat shown in FIG. 1; FIG. 8 is a bottom view of the thermostat shown in FIG. 1; FIG. 9 is an upper perspective view of a second embodiment of a thermostat;

FIG. 10 is a lower perspective view of the thermostat shown in FIG. 9;

FIG. 11 is a front view of the thermostat shown in FIG. 9; FIG. 12 is a rear view of the thermostat shown in FIG. 9; FIG. 13 is a left-side view of the thermostat shown in FIG. 9;

FIG. 14 is a right-side view of the thermostat shown in FIG. 9;

FIG. 15 is a top view of the thermostat shown in FIG. 9; FIG. 16 is a bottom view of the thermostat shown in FIG. 9; FIG. 17 is an upper perspective view of a third embodiment of a thermostat;

FIG. 18 is a lower perspective view of the thermostat shown in FIG. 17;

FIG. 19 is a front view of the thermostat shown in FIG. 17; FIG. 20 is a rear view of the thermostat shown in FIG. 17; FIG. 21 is a left-side view of the thermostat shown in FIG. 17;

FIG. 22 is a right-side view of the thermostat shown in FIG. 17;

FIG. 23 is a top view of the thermostat shown in FIG. 17; and,

FIG. 24 is a bottom view of the thermostat shown in FIG. 17. The broken lines shown in the figures are for illustrative purposes only and form no part of the claimed design.
